DESIGN FOR A TRAILER

Fred. E. Kaunitz and Lester R. Kaunitz, Bay City, Mich.

Application April 2, 1934, Serial No. 51,299

Term of patent 7 years

To all whom it may concern:

Be it known that we, FRED. E. KAUNITZ and LESTER R. KAUNITZ, citizens of the United States, and residing at Bay City, in the county of Bay and State of Michigan, have invented a certain new, original, and ornamental Design for Trailers, of which the following is a specification, reference being had to the accompanying drawing, forming a part thereof.

In the drawing—

Fig. 1 is a side elevation of the trailer with the draw bar broken away.

Fig. 2 is a back elevation.

Fig. 3 is a front elevation.

What we claim is:

The ornamental design for a trailer, as shown.

FRED. E. KAUNITZ.
